United States Patent Office

Des. 204,431

Patented Apr. 12, 1966

204,431

COVER FOR SURF BOARDS

Howard C. Glasgow, 9325 Carmichael Drive,
La Mesa, Calif.

Filed Mar. 22, 1965, Ser. No. 84,387

Term of patent 3½ years

(Cl. D71—1)

FIG. 1

FIG. 2

FIG. 3

FIG. 4

FIG. 5

I claim:
The ornamental design for a cover for surf boards, as shown and described.
